UNITED STATES PATENT OFFICE.

JOHN MORTIMER TALLANTYRE, OF NEW BRIGHTON, ENGLAND.

CLOSURE FOR COLLAPSIBLE CAPSULES.

1,361,199.

Specification of Letters Patent.

Patented Dec. 7, 1920.

Application filed September 25, 1917. Serial No. 193,151.

To all whom it may concern:

Be it known that I, JOHN MORTIMER TALLANTYRE, a subject of the King of Great Britain, residing at New Brighton, in the county of Chester and Kingdom of England, have invented certain new and useful Improvements in Closures for Collapsible Capsules, of which the following is a specification.

10 The present invention relates to an improved closure for collapsible tubes or the like of the type in which the sealing cap for the tube is carried on a pair of arms mounted on the tube or the like to swing 15 to one side of the exit orifice in the neck of the same when desired, but which can be screwed down over this.

In the improved constructions of the present invention projecting eyes, pins or other like means are provided on the body of the 20 capsule to receive and form pivotal connections for the ends of the arms carrying the cap.

The invention is more particularly described with reference to the accompanying drawings, in which:—

Figure 1 is a view showing a tube with the improved closure.

Fig. 2 is a partial view showing a modified form,

Fig. 3 shows a different mode of attachment.

The neck 1 of a collapsible capsule or tube

2 is provided with a pair of pins 3 which are engaged by eyes 4 on shanks 5 carried by a head 6 which is perforated to receive a threaded spindle 7 having an operating head 8. This operating head can be in the form of a disk as shown in Fig. 2, or it can be in the form of a shrouding cap such as 40 9, Figs. 1 and 3. The spindle 7 also carries a plug 10 which is recessed at 11 to receive a cork washer or the like which is adapted to be screwed down upon the opening 12 of the tube. As shown in Fig. 3, lugs 13 may 45 be provided on the tube head 1 to engage eyes on the shanks 5 of the head 9.

What I claim is:—

As an article of manufacture, a stopper comprising in combination arms supporting 50 a cross head having a threaded perforation, a threaded spindle in said perforation, a hollow cap integral with said spindle shrouding it and said crosshead and a sealing cap integral with said spindle and attached on 55 the opposite side of said crosshead to the attachment of the cap.

In witness whereof, I have hereunto signed my name this 7th day of September 1917, in the presence of two subscribing 60 witnesses.

JOHN MORTIMER TALLANTYRE

Witnesses:

J. VICTOR ARMSTRONG,
M. HAILES.
